UNITED STATES PATENT OFFICE.

JOHN NELSON, OF PERU, ILLINOIS.

RHEOSTAT.

SPECIFICATION forming part of Letters Patent No. 770,472, dated September 20, 1904.

Application filed July 5, 1904. Serial No. 215,385. (No model.)

To all whom it may concern:

Be it known that I, JOHN NELSON, a citizen of the United States, residing at Peru, in the county of LaSalle and State of Illinois, have 5 invented a new and useful Improvement in Rheostats, of which the following is a specification.

My invention relates particularly to rheostats which may be employed for producing 10 a wide variation in the resistance of an electric circuit; and my primary object is to provide a rheostat of this character of simple and compact construction which is capable of introducing into a circuit resistance which may 15 be readily varied from zero to the highest resistance usually desirable in this class of instruments.

My invention is illustrated in the accompanying drawings, in which—

20 Figure 1 represents a plan view of a rheostat embodying my improvements; Fig. 2, a side elevational view of the same viewed as indicated at line 2 of Fig. 6; Fig. 3, a longitudinal section taken as indicated at line 3 of Fig. 6; Fig. 4, a longitudinal section taken as indicated at line 4 of Fig. 6; Fig. 5, an end elevational view; Fig. 6, a transverse section taken as indicated at line 6 of Fig. 3; and Fig. 7, a broken transverse section, partly 25 grammatic in its nature, illustrating the manner in which the resistance-coils are supported.

In the preferred construction, A represents a frame which may be conveniently attached to a wall within easy reach from the floor; 30 B B', two series of standards having insulated connections, respectively, with the two longitudinal or vertical frame members; B² B³, two series of contact-blocks arranged in parallel longitudinal columns and having insulated connections at one side of the longitudinal center of the frame and having insulated connections with the longitudinal frame member B⁴; C C', two series of resistance-coils arranged in parallel columns at opposite 45 sides of the contact-blocks B² B³; D, a slide connected with the contact-blocks; E, a longitudinally-extending conductor or bar forming a portion of a short-circuiting device and arranged beneath the slide D and having insulated connection with the frame member B⁴;

F, a switch-lever pivotally connected with one end of the bar E; G, a conductor in circuit with a battery G' and connected with the corresponding end members of the standards B B'; S M, contact-blocks connected, respectively, with the corresponding end members of the contact-blocks B² B³, and W a contact-block located adjacent to the block M and having insulated connection with the adjacent member B³.

Commencing with the near or lower end of the device, the first one of the standards B is joined by a rod b to the first one of the blocks B², the second one of the standards B is joined by a rod b' to the third one of the blocks B², 65 the third one of the standards B is joined by a rod b'' to the fifth one of the blocks B², and the fourth one of the standards B is joined by a rod b''' to the seventh one of the blocks B². Similarly the standards B' are joined by 70 a series of rods c to c', inclusive, to alternate ones of the blocks B³.

The first resistance-coil C is connected at its outer end with the upper portion of the standard B and at its inner end with the lower portion of the block B². The second coil C is connected at its outer end with the lower portion of the standard B and at its inner end with the upper portion of the block B². The same method is followed throughout in connecting 75 the remaining coils of the C series with their appropriate standards and contact-blocks. The coils are grouped in pairs, so that two coils lie between each two pairs of rods. In a similar manner the coils of the C' series are 80 grouped and connected with their respective standards and contact-blocks. Thus the first coil C' is connected at its outer end with the upper portion of the standard B' and at its inner end with the lower portion of the contact-block B³, the second coil is connected at 85 its outer end with the lower portion of the second standard B' and at its inner end with the upper portion of the second contact-block B³, and so on.

The uppermost pair of contact-blocks are 90 entirely insulated and may serve to receive the slide when all of the coils are in use. The two columns of contact-blocks B² B³ are spaced 95 to receive the slide D and have inturned flanges, 100

as shown in Fig. 6. The slide comprises an upper member d ; a lower member d' ; depending bolts d^2 , secured to the upper member d and passing loosely through the member d' ; springs d^3 , confined on the lower ends of said bolts and serving to yieldingly force the members d d' together to insure intimate contact with the flanges of the blocks B^2 B^3 , and a yielding shoe d^4 , depending from the member d' and bearing on the bar E . The member d is equipped with a handle d^5 .

Assuming the switch-lever F to be in the position shown in Fig. 5, it is evident that the bar E performs no function. Assuming the switch-lever to be upon the block M , which is electrically connected with the first one of the series of blocks B^3 , it is evident that the coils of the C' series will be short-circuited and the current will pass through the rod e , the first one of the blocks B^3 , the block M , the switch-lever F , the bar E , shoe d^4 , slide D , rod b' , and thence back through the "cut-in" coils of the C series to the battery. Assuming the lever F to be on the contact-block S , the coils of the C series will be short-circuited, while the coils of the C' series will be in use. In this explanation it is to be understood that the slide D has been assumed to be in the position shown in Fig. 1 and that the coils concerned are the coils below the slide. Obviously the slide may be raised or lowered to "cut in" or "cut out" resistance.

From the foregoing explanation it will be understood that with the slide D in a given position a weak, medium, or strong current may be obtained, according to the position of the switch-lever F , and it will be noticed that the reference-letters of the blocks W , M , and S correspond with the initials of the words "Weak," "Medium," and "Strong." In practice the blocks are so marked on the apparatus. As probably has been inferred, the coils C are of greater length than the coils C' , and hence of greater resistance. The grouping of the coils and the arrangement of the rods is an advantageous one, as will be readily understood.

A rheostat of the construction set forth is of particular value in connection with currents of low voltage—such as are employed, for instance, in electroplating. The standards and contact-blocks are of suitable size and shape to enable the connections to be made in the manner stated; but obviously the device may be altered in these particulars without departure from my invention.

It readily will be understood that the mechanical construction may be varied greatly without departure from my invention. Hence I wish to be understood as intending no undue limitation from the foregoing detailed description.

What I regard as new, and desire to secure by Letters Patent, is—

65 1. The combination of a series of coils of a

given resistance connected with a series of contact members, a second series of coils of less resistance connected with a second series of contact members, a slide connected with said contact members, connections joining the free ends of appropriate coils of each series, and means for short-circuiting either series of coils, for the purpose set forth.

2. The combination of two series of resistance-coils and two series of contact members connected therewith, a slide adapted to move on said contact members, suitable connections at the free ends of the coils, a conductor, and a contact-piece connected with said slide and engaging said conductor, for the purpose set forth.

3. The combination of two series of resistance-coils and two series of contact members connected therewith, a slide adapted to move on said contact members, suitable connections at the free ends of the coils, a conductor extending parallel with the traverse of the slide, a contact-piece carried by the slide and contacting with said conductor, and a switch for connecting said conductor with the electric circuit, substantially as and for the purpose set forth.

4. The combination of two series of resistance-coils and two series of contact members connected therewith, a slide adapted to move on said contact members, suitable connections at the free ends of the coils, a conductor back of the path of said slide, a contact-piece connected with said slide and engaging said conductor, and a switch connected with said conductor and adapted to be connected with an end member of either series of contact members, substantially as and for the purpose set forth.

5. The combination of a frame, two series of parallel standards supported at the lateral margins thereof, two series of contact-blocks arranged in rows parallel with said standards and intermediate the same, two series of coils arranged in parallel rows on opposite sides of said contact-blocks, the coils of each series being connected with their respective standards and contact-blocks to cause the current to traverse the coils, and a slide connected with said contact-blocks, substantially as and for the purpose set forth.

6. The combination of a rectangular frame, insulated standards supported along on lateral margins of the frame, insulated contact-blocks arranged in two columns parallel with the sides of the frame, two series of coils supported on the contact-blocks and standards, and a slide connected with the contact-blocks, substantially as and for the purpose set forth.

7. The combination with a suitable frame of two series of standards arranged along opposite sides of the frame, two parallel columns of contact-blocks arranged between the series of standards, a conductor connecting one end standard of one series with the adjacent con-

- tact-block, a conductor connecting the corresponding end standard of the other series with the adjacent contact-block, coils connected with said last-mentioned two standards and 5 with the next adjacent contact-blocks, coils connected with said last-named contact-blocks and with the next adjacent standards, additional coils connected with the standards and with the remaining contact-blocks in proper 10 sequence, and a slide movable on said contact-blocks, substantially as and for the purpose set forth.
8. The combination of two series of standards, two series of contact-blocks, two series 15 of resistance-coils, two series of conductors, the coils of each series being arranged in pairs and connected with appropriate contact-blocks and standards, and the standards being con-

nected by said conductors to the contact-blocks which are left unconnected with the coils, and 20 a slide movable on said contact members, substantially as and for the purpose set forth.

9. The combination of a suitable frame, two series of standards, two series of contact-blocks, a slide, a conductor located beneath the 25 path of said slide, two series of resistance-coils, an insulated contact member, and a switch serving to connect said conductor with one of the end blocks of either series or with the said insulated contact member, at will, substantially as and for the purpose set forth. 30

JOHN NELSON.

In presence of—

WALTER N. WINBERG,
F. M. WIRTZ.
